UNITED STATES PATENT OFFICE.

FRANK LESLIE WEBSTER, OF WAIALUA, TERRITORY OF HAWAII.

MACHINE FOR CONVEYING AND LOADING CROPS.

SPECIFICATION forming part of Letters Patent No. 740,066, dated September 29, 1903.

Application filed December 4, 1902, Serial No. 133,934. (No model.)

To all whom it may concern:

Be it known that I, FRANK LESLIE WEBSTER, a citizen of the Dominion of Canada, residing at Waialua, Island of Oahu, Territory of Hawaii, have invented certain new and useful Improvements in Machines for Conveying and Loading Crops and Merchandise; and I hereby declare the following to be a full, clear, and exact description of the invention, such as will enable others skilled in the art to which it appertains to make and use the same.

My invention is designed principally for use on sugar plantations where main lines of railway are established to different parts of the plantation with portable railway-tracks branching off from the main lines to convey the cane when loaded on cars from the fields to the sugar factory. The present method of loading the cars is by hand, the laborers picking up the cut cane and carrying it to and depositing it on the car, a ladder being used to gain the top. My invention is intended to do away with much of this manual labor and without adding the expense of laying special tracks or interfering with the passage of cane-cars over the railways. My machine is mounted on a truck to run on the plantation-railways and is arranged to permit of empty cane-cars being hauled up an inclined track and over the platform, passing through the framework of the machine, and down a similar inclined track on the opposite end. It is provided with cable-drums, any one of which may be connected at the will of the operator, by means of friction-clutches, with their shafts driven by a suitable motor, such as a gasoline-engine. These drums are preferably arranged in two sets, one set for working the cables on each side of the railway and each set consisting of two hauling-cable drums and one hoisting-drum with brake-band. On top of the framework are mounted two jib-cranes for the hoisting-cables. The cut cane in the field is bundled by laborers, the bundles being hauled by the cables toward the machine and then elevated by the hoisting-cables to a suitable height to clear and to swing over and

be dropped in the desired position on the car, as will hereinafter more fully appear.

In the accompanying drawings, Figure 1 represents a top plan view of my machine; Fig. 2 represents an end elevation of the same. Fig. 3 represents a side elevation of the same. Fig. 4 represents a top plan view of the platform of the machine mounted upon its car-truck. Fig. 5 is a diagrammatic illustration of the apparatus, showing a preferred method of operating the cables.

Similar letters of reference indicate similar parts throughout the several views.

Referring to the drawings, it will be noted that the machine is mounted upon a car-truck suitable for the portable track. Upon this truck *f* is secured a frame *p p' p''*, carrying flanged wheels *h*, with their axles radiating horizontally from the center of the truck, said wheels being arranged equally spaced about a circle whose center is also that of the truck, as shown in Fig. 1 and Fig. 4. Upon these wheels *h* rests the platform *a*, constituting a turn-table, which may be turned and wedged or locked in any desired position, only the working position being shown in the several views. In transporting the machine it is turned horizontally to a position at right angles to that shown. Upon the platform *a* are laid rails forming a track of the same gage as the plantation-railways, from each end of which a section of portable track *i i'* extends on a downward incline to connect the track on the platform with the track on which the machine rests. These inclined tracks are removable and are provided with swing-hinged struts *k k'*, &c. (Shown in Fig. 3.) Upon the platform *a* is secured a framework *a'*, suitably braced and of sufficient height and width to permit of an empty cane-car being passed through it. Upon this frame *a'* is mounted a mast *c*, with its step *m* and stiff leg *l* supporting two booms or jib-cranes *b* and *b'*. The mast *c* may be slightly inclined, as shown in Fig. 3, so that the cranes will tend to swing over the car to be loaded. The platform *a* is extended outside of the frame *a'* on two opposite sides, one of which extensions supports

the gasoline-engine or other motor *g*, geared to run the drum-shafts *w* and *w'*, and on the other extension is located a water-tank *q*, which not only tends to balance the platform, but supplies the water for cooling the engine-cylinder, the water circulating through piping placed above and below the frame *a'* and connecting the tank *q* with the water-jacket of the engine *g*. Upon the shaft *w* are loosely mounted the hauling-cable drums *d* *d'* and the hoisting-cable drum *e*, any one of which may be caused to revolve with the shaft *w* by its friction-clutch operated by the lever *y*, *y'*, or *y''*. (Shown in Fig. 3.) The hoisting-drum *e* is also provided with a brake-band *z*. The hauling-cables from the drums *d* *d'* pass up over the sheaves *r* *r'* and are run out and attached to the bundles of cane to be pulled toward the machine. The hoisting-cable passes up from its drum *e* over the sheaves *n* *n'*, *s*', and *n* *s* at the outer end of the boom *b*. These drums and cables being for use on the motor side of the railway, a duplicate arrangement is provided for working on the opposite side, (shown in Fig. 1,) the hauling-cables from the drums *d* *d'* passing over the sheaves *n* *r* *s* and *n* *r'*, respectively, and the hoisting-cable from its drum *e* runs over one of the sheaves *n* *s*, then over *n* *s*', *s* *s'*, and *n* *s* at the end of the boom *b'*, *s*' and *s* being single blocks, *n* *n* *s* being plain sheaves, *r* and *r'* being sheaves whose frames are mounted to turn in a horizontal plane through about one hundred and eighty degrees, and *r* *s* and *r* *s'* being similar to *r*, but arranged to turn in a vertical plane. Under the four corners of the platform *a* are secured cup-shaped castings *x*, into which round headed screw-jacks *j* are placed to stiffen the platform when the machine is in use. An awning *t* may be attached to the frame *a'* to protect the motor from the weather. (Shown in Fig. 2.) The car-truck *f* is provided with toggle-jointed brakes operated by the lever *v*. (Shown in Fig. 4.)

45 The mode of operation will be apparent. The machine is run over the main track to the field being harvested and hauled out on the portable track convenient to the cane that is to be loaded, the jib-crane end of the machine being turned toward the main track. The brakes are then set. The jacks are applied to support the platform-corners. The inclined portable tracks are placed in position, (shown in Fig. 3,) over which the cane-cars to be loaded are hauled until all but one have passed through the frame of the machine, the last car being left on the incline under the jib-crane. The cane having been bundled by the laborers, each sling holding several hundred pounds of cane, the crane-hoisting cables are used to pick up the bundles that are reasonably near the machine and raise them to a suitable height to swing clear of the car-stakes, a man turning and guiding the bundle, so that it may be dropped in the place and in the direction desired on the car. A

man at the tag-rope attached to the end of the hoisting-cable at the same time pulling on his rope disengages the sling from the cane just dropped and pulls the cable down and attaches another bundle. While this is being done a second bundle is being hoisted and dropped into the car from the second jib-crane, these operations being repeated until the car is loaded, whereupon the car is pushed toward the main line and an empty car run through the machine to the loading position under the cranes. The hauling-cables at the same time are being run out and used to draw the bundles from a distance to where they may be reached by the crane-cables. By having two hauling-cables for working on each side of the railway they may be arranged by a rope attached to their ends passing over a snatch-block anchored in the field, so that while one cable is hauling a bundle in it is at the same time pulling the other cable out to be attached to another bundle of cane, as illustrated in Fig. 5. The machine and the cars may be moved by means of the power from the motor on the machine.

While I have described my machine as applied to the conveying and loading of sugar-cane, it will appear that it may be applied to any similar crop or may be used for the loading of stone, timber, or other merchandise.

Having thus fully described my invention, what I claim as new, and desire to secure by Letters Patent, is—

1. A machine for conveying and loading crops and the like, having its platform mounted upon wheels arranged in a circle and axled to the frame of its car-truck, such that the platform may be turned in a horizontal plane thereon, an elevated frame above the platform for supporting at one end a mast and its boom, and a track on said platform having inclined sections to connect with the track on which the machine rests; substantially as described. 100

2. A machine for conveying and loading crops and the like, having a rotary platform, a track upon said platform and inclined rails to connect said platform-track with the track on which the machine rests, substantially as described. 105

3. A machine of the kind described, turn-tabled on its car-truck and having inclined rails provided with hinged supports; substantially as described. 110

4. A machine of the kind described, having a truck upon which the machine is turn-tabled, a car-track on its platform, inclined rails with hinged supports and an opening in its frame which permits of a car being hauled through said frame over the track on the platform; substantially as described. 125

5. A machine of the kind described, turn-tabled on its truck, a frame above the platform supporting one or more cranes, said frame permitting the passage of a car through same, inclined rails with hinged supports, 130

740,066

3

and a motor mounted on the platform for operating the hauling and hoisting cables; substantially as described.

5. A machine of the kind described, having the hauling-cables in pairs, such that while one of them is hauling in the load it is at the same time pulling the other cable out.

In testimony whereof I have signed my name to this specification in the presence of two subscribing witnesses.

FRANK LESLIE WEBSTER.
